(57) **CLAIM**

The ornamental design for a handle for laparoscopic device, as shown and described.

DESCRIPTION

FIG. 1 is a perspective view of a handle for laparoscopic device in accordance with the present design;
FIG. 2 is a rear view of the handle for laparoscopic device of FIG. 1;
FIG. 3 is a front view of the handle for laparoscopic device of FIG. 1;
FIG. 4 is a top view of the handle for laparoscopic device of FIG. 1;
FIG. 5 is a bottom view of the handle for laparoscopic device of FIG. 1;
FIG. 6 is a left side view of the handle for laparoscopic device of FIG. 1; and,
FIG. 7 is a right side view of the handle for laparoscopic device of FIG. 1.

In FIGS. 1-7, the features of the handle for laparoscopic device shown in phantom lines depict environmental subject matter only and form no part of the claimed design.

1 Claim, 7 Drawing Sheets
